UNITED STATES PATENT OFFICE.

STEPHEN E. ELLIOTT, OF WEST SALEM, ILLINOIS.

WIRE-HOLDER.

1,105,412.

Specification of Letters Patent. Patented July 28, 1914.

Application filed April 14, 1914. Serial No. 831,752.

To all whom it may concern:

Be it known that I, STEPHEN E. ELLIOTT, a citizen of the United States, and a resident of West Salem, in the county of Edwards 5 and State of Illinois, have made certain new and useful Improvements in Wire-Holders, of which the following is a specification.

My invention is an improvement in wire holders, and has for its object to provide a 10 device of the character specified, especially adapted for holding wire fencing during the stretching thereof, and wherein means is provided for permitting the clamping bars that engage the fencing throughout its 15 height, to be easily and quickly placed on the fence or to be removed therefrom, without the necessity of removing or replacing taps, nuts and the like.

In the drawings:—Figure 1 is a front view 20 of the improved holder, Figs. 2 and 3 are sections on the lines 2—2, and 3—3, respectively, of Fig. 1, Fig. 3 looking in the direction of the arrows adjacent to the line, and Fig. 4 is a perspective view of one of the 25 clamping elements detached.

The present embodiment of the invention is shown in connection with a wire fence 1. The holders consist of bars or plates 2 and 3, of wood or the like, the said bars being of a 30 length to engage the entire width of the fence, and to extend above and below the same. Each of the bars 2 and 3 is provided on its outer face with longitudinally extending reinforcing strips or plates 4 and 5 of 35 metal, as for instance sheet iron or the like, the said strips extending from one end of the bars to the other, and being secured to the bars by means of screws 6 or the like. At suitable points, preferably near the ends, the 40 bar 2 is provided with a transverse opening 7, and the bar 3 is provided with a similar opening 8, registering with the opening 7, and the outer end of the opening 8 is countersunk, as shown at 9. A pin 10 engages 45 the opening 8 of the bar 3, the said pin having a head 11 received in the countersink 9, and the strip 5 is arranged above the head of the pin, so that the pin cannot become disengaged from the bar 3 and the pin is of a 50 length to extend entirely through the bar 3, and to the plate 4 of the bar 2, the said pin being adapted to engage the opening 7. The pins 10, of which there are 2 in the present 55 instance, are designed to act as guides for properly positioning the bars 2 and 3 with respect to each other. The strip or plate 4

of the bar 2 extends over the outer end of the opening 7, as shown in Fig. 2. At regular intervals the bar 2 is provided with transverse slots or elliptical openings 12, the long 60 axis of the openings being parallel or coinciding with the long axis of the bar, and the said openings extend through the reinforcing strip 4. The bar 3 is provided with similar openings 13, adapted to register with 65 the openings 12 of the bar 2, and the openings 13 extend through the reinforcing strip 5. A series of clamping means is provided, one of the said means operating in each pair of registering openings 12—13. Each of the 70 clamping means consists of a rod 14, provided at one end with a transverse head 15 of a length and width to pass through the slots or openings 12 and 13, and of a length to extend across the said openings, to hold 75 the rod from reverse movement when the said head is turned transverse to the slot.

A handle 16 is connected with each rod at the opposite end from the head, each of the said handles having a pair of cam shaped 80 heads or lugs 17 at one end. The lugs 17 are spaced apart to fit over the end opposite from the head of the rod 14, and a pivot pin 18 is passed through registering openings in the lugs and in the rod, for pivoting the 85 handle to the pin. The lugs 17 are so shaped, that when the handle 16 is approximately parallel with the bars 2 and 3 the head 15 of the rod will be pressed tightly 90 against the reinforcing strip 4 of the bar 2, and the bars will be clamped firmly together on the fencing 1. The handles are of such length that when in the position of Fig. 1, that is in contact with the reinforcing strip 5, they will not extend to the next lower set 95 of registering slots.

The inner face of the bar 3 is longitudinally grooved throughout its length, as indicated at 19, and the inner face of the bar 2 is provided with a longitudinally extending rib 20. The rib 20 is of less width than the groove 19, so that when the clamping devices are in clamped position a portion of the fencing wire will be offset into the groove 19. During the stretching of wire fencing 100 it is essential that the wire be grasped throughout its width and firmly held, and the usual clamping bars are held together by bolts and nuts. It is obvious that the parts cannot be quickly disengaged when so 105 held together. With the present arrangement, however, it is only necessary to place

the bars, insert the several rods through the registering slots or openings, turn the rod to bring the head transverse to the said slot, and then swing the handle into the full line 5 position of Fig. 2, until the free end of the handle contacts with the reinforcing strip 5.

The cam lugs 17 are so arranged that when the free end of the handle 16 contacts with the reinforcing strip 5, the highest portion 10 of eccentricity of the cams will be a little off center, thus locking the handle against reverse movement. The rods 14 are of such length, and the bars 2 and 3 with their reinforcing strips are of such width, that when 15 the handles are in contact with the reinforcing strip 5, the bars will be firmly clamped on the wire, to hold the same during the operation of stretching. In practice the bars 2 and 3 will have a length of five feet, 20 a width of three inches, and a thickness of one and one-half inches.

I claim:—

1. A device of the character specified, comprising a pair of bars, one of the bars 25 having on its inner face a longitudinally extending groove, and the other bar having a longitudinally extending rib of less width than the groove, each of the bars having a reinforcing strip on its outer face at the center thereof, each bar having a series of slots extending through the reinforcing strip, the slots extending longitudinally of the bars and being spaced apart at regular intervals, and the slots of one bar registering with the slots 30 of the other bars, a clamping device for each 35 pair of registering slots, each of the said devices comprising a rod having a head adapt-

ed to pass through the slots and to engage transversely of the slots, and a handle pivoted to the other end of each rod, each handle having a pair of cam shaped lugs engaging the opposite sides of the rod and pivoted thereto for drawing the rod toward the handle when the handle is turned into parallelism with the bars, one of the bars 40 having laterally extending guide pins on its inner face and near its ends, and the other bar having openings for receiving the guide pins.

2. A device of the character specified, 50 comprising a pair of bars, each of the bars having a reinforcing strip on its outer face at the center thereof, each bar having a series of slots extending through the reinforcing strip, the slots extending longitudinally of the bars and being spaced apart at regular intervals, and the slots of one bar registering with the slots of the other bars, a clamping device for each pair of registering slots, each of the said devices comprising 55 a rod having a head adapted to pass through the slots and to engage transversely of the slots, and a handle pivoted to the other end of each rod, each handle having a pair of cam shaped lugs engaging the opposite sides of the rod and pivoted thereto for drawing the rod toward the handle when the handle is turned into parallelism with the bars.

STEPHEN E. ELLIOTT.
